UNITED STATES PATENT OFFICE.

PEMBERTON LUNDY, OF BOSTON, MASSACHUSETTS.

DESIGN FOR A SYRINGE-NOZZLE.

SPECIFICATION forming part of Design No. 34,364, dated April 16, 1901.

Application filed March 21, 1901. Serial No. 52,241. Term of patent 7 years.

To all whom it may concern:

Be it known that I, PEMBERTON LUNDY, of Boston, in the county of Suffolk and State of Massachusetts, have invented and produced a new and original Design for Syringe-Nozzles, of which the following is a specification, reference being had to the accompanying drawings, forming part thereof.

Of said drawings, Figure 1 represents the article in side elevation, and Fig. 2 represents the same in end elevation.

The reference-letter *a* designates a nozzle-head rounded or convexed in contour and tapered to a comparatively blunt upper end or point, in which there is a round hole *b*. Said head is formed at the base with an encircling shoulder *c*, and the surface of the head is longitudinally grooved or channeled, the grooves *d* commencing at points a short distance back from the hole *b* and extending obliquely to the base of the head and through the shoulder *c*. An elongated stem *e* is connected with the base of the head by a substantially con-

ical portion *f*, slightly concaved. The whole structure is integral and the exterior surfaces merge into each other, obviating sharp angles.

The characteristic features of the design are the rounded or convexed head brought to a comparatively blunt point and the reduced and elongated stem, together with the conical portion between it and the base of the head, the latter having a series of longitudinal grooves.

It will be seen that an article of this design is shapely in appearance as well as useful.

Having thus described my invention, what I claim as new is as follows:

The design for a syringe-nozzle substantially as herein shown and described.

In testimony whereof I have signed my name to this specification, in the presence of two subscribing witnesses, this 20th day of March, A. D. 1901.

PEMBERTON LUNDY.
